CLAIM

The ornamental design for a computer workstation, as shown and described.

DESCRIPTION

FIG. 1 is a front perspective view of the computer workstation showing our new design, showing the keyboard thereof in a fully parked position and the video display unit turned slightly towards the left;

FIG. 2 is a front perspective view thereof, showing the keyboard in a half-parked position and the video display unit turned slightly towards the right;

FIG. 3 is a left-front perspective view thereof on a reduced scale, showing the keyboard in a half-parked position and the video display unit facing the front of the keyboard;

FIG. 4 is a front perspective view thereof on a reduced scale, showing the keyboard fully positioned on the work surface;

FIG. 5 is a left side view thereof, showing the keyboard in a fully parked position;

FIG. 6 is a rear view, showing the keyboard in a fully parked position;

FIG. 7 is a greatly enlarged fragmentary view thereof, showing the keyboard in a fully parked position, the keyboard being broken away for purposes of disclosure;

FIG. 8 is a greatly enlarged fragmentary view thereof, showing the keyboard in a fully parked, elevated position;

FIG. 9 is a greatly enlarged fragmentary view thereof, showing the keyboard in a half-parked position, the keyboard being broken away for purposes of disclosure;

FIG. 10 is a greatly enlarged fragmentary view thereof, showing the keyboard in a half-parked, elevated position.
